WOMAN'S UNDERGARMENT

Sylvia Roodner, New York, N. Y.

Application February 10, 1949, Serial No. 75,579

5 Claims. (Cl. 2—224)

1

This invention relates to women's undergarments, more particularly to a new and improved pantie.

Its objects are to provide a pantie undergarment having the following distinguishing features:

1. It is comfortable for wearing under all normal conditions of use, and conforms itself to the movements of the wearer's body;

2. It eliminates side seams, thereby preventing tension or pulling on the seams and tearing of the garment;

3. It provides a smooth and comfortable fit as the garment hugs the wearer and still permits maximum freedom of movement;

4. It is graceful and pleasing in appearance;

5. It is simple in construction and hence economical to manufacture;

6. The back and front panels, which are integral, are so cut from a single blank of material so that the back section is on the bias, which provides ease in movement. When the wearer is at rest, the back hugs the body and does not bulge;

7. The cutting in the manner indicated in the preceding point imparts to the front of the garment the feature that riding-up of the garment is prevented and discomfort to the wearer is avoided;

8. It includes a novel form of the front insert which serves as the medium for connecting the garment into a unit, the said front insert having an integral depending portion which forms a part of the crotch unit. This eliminates any pulling action and prevents the tearing of the seams. In addition, the said front insert renders the garment exceedingly comfortable to the wearer and provides a better fitting garment. Because of the said construction, the garment will remain in position when the legs of the wearer are raised;

9. It has a novel crotch construction which eliminates bunching and bulging at the crotch area, and which provides fuller and snugger coverage between the wearer's legs, the legs thereby being adequately covered and protected from discomfort, chafing, rubbing and irritation when perspiration is present.

Further objects and advantages of the present invention will be apparent from the following description and from the drawing which accompanies said description.

A preferred form of this invention is shown in the accompanying drawing in which:

Fig. 1 is a front elevational view of a pantie- 55 undergarment embodying the invention,

2

Fig. 2 is a rear elevational view thereof,

Fig. 3 is a sectional view on the line 3—3 of Fig. 1,

Fig. 4 is an elevational view of the underneath portion of the undergarment,

Fig. 5 is a sectional view on the line 5—5 of Fig. 1, and

Fig. 6 is a sectional view on the line 6—6 of Fig. 4.

10 Referring to the drawing, the reference letter B designates the back portion or panel of the pantie undergarment, and F₁ and F₂ designates the respective front left and right portions or panels. The said back and front panels are formed from a single piece or blank of fabric (woven or knitted) cut on the bias. That is cut at approximately an angle of 45°. Reference to Figs. 1 and 2 will disclose angular lines on the back and front panels, the direction in which these several lines extend indicating the direction of the stretch of the said panels.

15 It will be discerned from Fig. 3, that there are no side seams whatsoever in the undergarment herein. Such side seams are therefore eliminated by reason of the fact that the back panel B and its integral complementary front panels F₁ and F₂ are cut from a single piece of material to form the body of the undergarment.

20 As shown in Fig. 1, the opposed free inner side edges 11 of front panels F₁ and F₂ are upwardly divergent, extending from points 10 adjacent the crotch portion to the waist-band W of the undergarment. An intermediate front panel F₃ connects front panels F₁ and F₂. Said connecting panel F₃ is of elongated inverted triangular shape, and its upwardly divergent side edges 12, are secured by the oblique lines of stitching 13 to the respective edges 11 of front panels F₁ and F₂. Connecting panel F₃ is cut on the straight, the vertically extending lines thereon (Fig. 1) indicating the direction of stretch of the said panel.

25 As shown in Figs. 1 and 4, intermediate front panel F₃ is provided with a depending, integral, generally diamond-shaped extension 14 which projects into and forms part of the crotch portion of the undergarment. The median portion 15 of said extension 14 is cut and connected together by vertical stitching.

30 The crotch portion of the undergarment is clearly illustrated in Fig. 4 of the drawing. The said crotch piece comprises the extension panel 14 and the two identical adjacent panels 16 and 17, all three said panels being connected to each other by the oblique lines of stitching 18 and the vertical line of stitching 19. All three crotch

panels are cut on the straight, the vertically extending lines therein (Figs. 1, 2 and 4) indicating the direction of stretch of the crotch piece.

Two leg holes or openings O are formed at the bottom of the undergarment when the crotch piece is connected to the lower ends of free opposed side edges of front panels F1 and F2 and the median portion of back panel B. This is effectuated by the front downwardly divergent lines of stitching 20, commencing at opposed points 10 and terminating at the front bottom edges of the undergarment, and the downwardly divergent lines of stitching 21 at the bottom center of back panel B.

It will be noted that the bottom central portion of back panel B is cut in inverted V-shape to accommodate the back section of the crotch piece. The lower portions of the inner opposed free sides of each of front panels F1 and F2 are cut from opposed points 10 on outwardly divergent lines terminating at the bottom of the undergarment, thereby forming the opposed oblique-angled points P1 and P2. The said projections P1 and P2 form an inverted V-shaped area therebetween, the front section of the crotch piece being accommodated therein.

The waist-band W is provided with an elastic band 22 which extends around said waist-band except between points X—X of intermediate front panel F3. This gives a smoother fit and eliminates gathers around the waist.

One of the principal features of the invention herein is the novel intermediate front connecting panel F3 and its depending projection 14 which forms a part of the improved crotch unit. All the advantages resultant from this construction have been heretofore pointed out and described in the statement of the objects of the invention. Another important feature of the invention is so cutting and securing the various panels that comprise the undergarment that horizontal, vertical and angular lines meet with each other to give extreme comfort and fullness, which was not hitherto obtainable in the usual type of pantie undergarment.

It will be understood that the foregoing is a description of the preferred embodiment of the invention given by way of illustration rather than by way of limitation. The invention may be modified in several ways in accordance with the skill of the art without departure from the essential features of the invention.

What is claimed is:

1. An undergarment comprising a main body panel cut from a single blank of material to present at the front thereof a pair of upwardly divergent side edges extending from the lower end thereof to the upper edge thereof, an intermediate

front panel having a pair of upwardly divergent side edges secured to said main body panel by stitching each side edge thereof to a respective side edge of said main body panel, a crotch section separate from the front panel and connecting said body panel and intermediate front panel to form leg openings for the undergarment, said intermediate front panel having an integral depending projection extending into and forming a part of said crotch section.

2. An undergarment comprising a back panel, a pair of spaced front panels, said back and front panels being formed of a single piece of material, an inverted triangular shaped intermediate front panel connecting said front panels, a crotch member separate from the front panel and connecting said back and front panels to form leg openings for the undergarment, the intermediate front panel having an integral depending diamond-shaped projection extending into and forming a part of said crotch member.

3. An undergarment in accordance with claim 2 in which an elastic band is secured to the upper continuous edge of the back panel and the two spaced front panels.

4. An undergarment in accordance with claim 2, in which the material of the panel forming the back panel and the two spaced front panels is cut on the bias, and the material of the intermediate front panel, its depending extension and the crotch section is cut on the straight.

5. An undergarment comprising a back panel, a pair of spaced side front panels, an intermediate front panel interposed between and connecting said side front panels, said intermediate front panel having opposite edges converging downwardly, a crotch member connecting said back and side front panels to form leg openings for the undergarment, said crotch member having a substantially V-shaped notch in the forward end thereof, and a substantially diamond-shaped projection integral with the intermediate front panel and separate from the crotch member and extending into the V-shaped notch therein and joined thereto.
